Specimen of the Design

II Berger's Design in Center pieces
No 18 Des Patented Oct 9 1860

Dec. 13 18

Contracted & corrected
Oct 17 1860

Henry Berger of New York, N.Y.
Letters Patent No. 1318 dated Oct. 2, 1860.
Nov. 7, 1860 Centre Piece

The schedule referred to in these Letters Patent and making part of the same.

To all whom it may concern:

Be it known that I, Henry Berger, of the City, County and State of New York, have invented a new and useful design in Centre pieces for the ornamentation of ceilings, and I hereby declare that the following is a full and exact description thereof, reference being had to the subjoined drawing, making part of this specification which represents the said design.

To enable others skilled in the art to proceed to describe this same,

The centre piece as represented in the annexed drawing consists of three principal parts to wit; firstly, the seat and its immediate surroundings; secondly, a square moulded frame partially hollowed out on its sides; thirdly, scrolls and arabesques surrounding the said frame.

The seat or internal centre is shaped in form of a crop with four buckets surrounded by an ornamental circle around which larger unnumbered leaves are forming, in such a manner as appears in the shape of a highly embellished shield in the renaissance style. This shield is enclosed by a heavily moulded frame, perfectly square, except the middle of each side of the square, which are bulged outward in a form nearly semi-circular and the spaces thereby obtained in the inside of the frame are filled up with leaves conforming to those of the circular shield and with those of the four corners of the square thus the whole space inclosed by the frame as well as the circular one around the seat represents an embellished renaissance shield.

On the outside of the frame there are large scrolls and arabesques so arranged that the largest portion of the scrolls connects with the upper and lower semi-circular portion of the frame and the smaller number of the same with the semi-circular portion of the frame situated on the right and left side. And these scrolls are also so arranged, that when the four parts forming the four extremes of the centre piece (two of which are marked on the drawing by being crossed with oblique lines) are removed from the same circular centre piece ensues; but without such removal the shape of the centre piece is an oblong one.

Des. 1318

The purpose of this design is the ornamentation of ceilings by being cast or moulded in stucco, plaster of paris, or similar material and attached to such ceilings.

That I claim as new and desire to secure by Letters Patent is the design in centre pieces for the decoration of ceilings substantially as described.
